CLAIM

The ornamental design for a sleeve with insert for holding two stored value cards, as shown and described.

DESCRIPTION

FIG. 1 is a perspective view of a sleeve with insert for holding two stored value cards according to the invention shown in a closed disposition;

FIG. 2 is a perspective view of the sleeve with insert for holding two stored value cards of FIG. 1 in an open disposition;

FIG. 3 is a front elevation view of the sleeve with insert for holding two stored value cards of FIG. 1;

FIG. 4 is a rear elevation view of the sleeve with insert for holding two stored value cards of FIG. 1;

FIG. 5 is a right elevation view of the sleeve with insert for holding two stored value cards of FIG. 1;

FIG. 6 is a left elevation view of the sleeve with insert for holding two stored value cards of FIG. 1;

FIG. 7 is a top plan view of the sleeve with insert for holding two stored value cards of FIG. 1; and,

FIG. 8 is a bottom plan view of the sleeve with insert for holding two stored value cards of FIG. 1.

The broken dash-dot-dot lines and arrows (—•—) showing in FIG. 2 are included for the purpose of illustrating direction to place the stored value cards on an insert of the sleeve with insert for holding two stored value cards.

The broken dash-dot-dot lines and arrows (—•—) showing in FIG. 2 are included for the purpose of illustrating direction to remove the insert holding the stored value cards from a portion of the sleeve with insert for holding two stored value cards.

The broken dashed lines (---) showing in FIGS. 1-6 are included for the purpose of illustrating portions of the sleeve with insert for holding two stored value cards that form no part of the claimed design.
